(57) **CLAIM**

The ornamental design for a tilt helm, as shown and described.

DESCRIPTION

FIG. 1 is a top, front isometric view of the tilt helm showing the new design;

FIG. 2 is a top plan view;

FIG. 3 is a side elevation, the other side being a mirror image;

FIG. 4 is a bottom plan view;

FIG. 5 is a front view;

FIG. 6 is a rear view;

FIG. 7 is a top, front isometric view of an alternate embodiment of the tilt helm showing the new design; and,

FIG. 8 is a bottom plan view of the alternate embodiment.

In all the figures, the broken lines are for illustrative purposes only and form no part of the claimed design. There are two different embodiments depicted above. The first embodiment is depicted in FIGS. 1–6. The second embodiment is depicted in FIGS. 7 and 8. The second embodiment is the same as the first embodiment except that the second embodiment lacks the loop-shaped molding found in the first embodiment.
